UNITED STATES PATENT OFFICE.

HIPPOLYTE JEAN MARIE PIERRE LA BASTIDE, OF LIMOGES, FRANCE.

DESIGN FOR A COVERED DISH.

SPECIFICATION forming part of Design No. 25,639, dated June 16, 1896.

Application filed March 30, 1896. Serial No. 585,523. Term of patent 7 years.

To all whom it may concern:

Be it known that I, HIPPOLYTE JEAN MARIE PIERRE LA BASTIDE, a citizen of France, residing at Limoges, in the Department of Haute-Vienne and Republic of France, have invented and produced a new and original Design for Dishes; and I do hereby declare the following to be a full, clear, and exact description of the same, reference being had to the accompanying drawing, forming a part thereof.

The principal feature of my design consists of a covered dish ornamented with composite designs resembling scroll and shell like decorations.

The drawing represents the face view of the dish.

From the base of the dish at either end A A there rises toward the upper part, but not reaching to it, an irregular series of scroll-like ornamentation. The handles B B, at the ends of the dish, are formed by the extension of these ornamentations.

The cover is irregular in its outline, conforming to the shape of the dish.

The handle C is formed by what resembles two scrolls of unequal size that are joined as shown in design.

On each side of the cover, rising from the periphery and continuing for a short distance toward the handle, is a series of shell-like ornaments D, which are met by a scroll-like decoration descending in a curve.

What I claim is—

The design for a covered dish substantially as herein shown and described. 35

In testimony whereof I affix my signature in presence of two witnesses.

HIPPOLYTE JEAN MARIE PIERRE LA BASTIDE.
